UNITED STATES PATENT OFFICE

ALFRED E. BUHRKE AND ALLEN F. HEETER, OF CHICAGO, ILLINOIS, ASSIGNORS TO R. H. BUHRKE COMPANY, A CORPORATION OF ILLINOIS

GOLF CLUB

Application filed September 26, 1930. Serial No. 484,535.

The invention relates to a new and improved construction of a golf club, particularly to the construction of a golf club of the type commonly referred to as an iron club, 5 that is, having a metallic head with an integral metal shank and provided with a metallic shaft.

The primary object of the invention is to provide improved means in a golf club of the 10 described character for securing a tubular metallic golf club shaft in the hosel of the metallic shank of an iron club head.

It is a further object of the invention to provide an improved construction for securing 15 a tubular metallic shaft in the hosel of the shank of an iron golf club head thereby avoiding the use of the common securement means consisting of the provision of registering holes in the shank wall around the hosel 20 and in the hollow metallic shaft in which a suitable locking rivet or pin is secured, since it is found that any cutting or drilling of the comparatively thin walls of the hollow shaft necessarily weakens them and renders the 25 shaft more liable to crystallization and failure at that point.

Other objects of the invention will appear from the following description which is directed to the preferred embodiments of the 30 invention, illustrated in the drawing forming a part of the specification, the novel features being set forth in the appended claims.

In the said drawing:

Fig. 1 is an elevation view of a complete 35 iron type of golf club to which the invention is shown applied.

Fig. 2 is an illustrative, longitudinal, sectional view of a fragment of the shank of an iron club head showing the lower extremity 40 of a steel shaft inserted in the hosel and ready to have the detached anvil plug, shown in the drawing, inserted by passing the same from the upper open end of the conical hollow shaft to the lower end thereof within the hosel, as illustrated in Fig. 3, Fig. 3 also 45 showing a specially formed locking plug designed to be inserted within the hollow steel shaft in the manner illustrated in Fig. 4 and finally driven to the locking position as shown 50 by the relative position of the parts in Fig.

5, Figs. 3, 4 and 5 being fragmental sectional views similar to Fig. 2.

Figs. 6 and 7 are views similar to Figs. 2 to 5 inclusive, illustrating the use of a modified form of locking device for securing the shaft 55 in the hosel in the shank of the club head.

The invention is adapted only for use in connection with tubular metallic shafted clubs, the shaft of which is designated in the drawing by the reference character 10, the 60 same being provided with the usual wrapped handle portion 11.

The reference character 12 designates the iron head of the club provided with an integral shank or neck portion 13 provided with 65 a central longitudinal opening or hosel 14 to receive the lower end of the conical or tapered shaft 10.

The invention is applicable to the hosel of any metallic necked club head but I prefer 70 to give the neck of the head the general shape of the frustum of a cone, that is, for balancing purposes, making the diameter of the neck portion 13 largest near the upper end thereof and tapering the same downwardly in the 75 usual manner to a point near where the blade or head portion begins to provide the usual widened portion 12, which carries the striking face.

Near the thickest portion of the neck 13, 80 which may be tapered at its upper extremity as indicated at 15 for the sake of appearance and to provide a slight resiliency in the upper end of the neck to prevent a tendency to kinking or crystallization of the shaft where 85 it enters the hosel, I provide a peripheral groove within the hosel on the neck 13 as indicated at 16.

17 is an anvil or wedge block that may be 90 formed at its lower extremity at 18 to correspond with the shape of the hosel opening 14 at the bottom thereof, so that when the anvil 17 is in its normal position as illustrated in Figs. 3 to 5 inclusive, the lower end thereof 95 will be firmly seated on the bottom of the hosel opening 14 providing an angular anvil surface at the upper end thereof in the transverse plane co-incident with the groove 16, as is illustrated also in Figs. 3 to 5 inclusive, 100 the conical wedging surface at the upper end

of the anvil 17 being designated by the reference character 19.

The anvil block 17 may be of a diameter to form a cross drive fit when it reaches the lower end of the hosel opening in the lower end of the tubular shaft.

In assembling the parts to secure the shaft 10 to the head of the club, if the shank 13 is drilled to provide the hosel opening 14 and the peripheral locking groove 16, the lower slightly conical or tapered end of the shaft will be driven to the position of the parts shown in Fig. 2, after which the cylindrical anvil plug 17 will be inserted in the enlarged upper end of the shaft and, by means of a driving rod, will be forced downwardly until it seats on the bottom of the hosel opening 14 as illustrated in Fig. 3 with the abruptly tapered upper end 19 thereof adjacent the peripheral groove 16. To secure the best results the anvil block 17 will preferably be formed of a comparatively hard metal or at least the upper end thereof adjacent the wedging surfaces 19 may be case-hardened in the usual manner. The tubular shafts 10 are generally constructed of steel and having a degree of hardness somewhat in excess of the material of the shank 13 of the head.

A cylindrical wedging block 20 of a diameter adapted to have a drive fit into the interior of a tubular shaft 10 will be next introduced on the interior of the shaft. This block 20 which is shown in Figs. 3 to 5 inclusive, will be provided with a central bore 30 35 40 45 50 55 60 65 at the lower end thereof, and this bore will be preferably enlarged at the lower extremity providing peripheral walls 22. When the cylindrical wedging block 20 is driven downwardly to seat upon the anvil block 17 by means of a driving rod, not shown, introduced through the open upper end of the tubular shaft 10, the peripheral widened portion 22 at the lower end of the block 20 will first contact with the angular portions 19 in the opening in the end of the anvil block 17 as most clearly shown in Fig. 4, after which the wedging block 20 may be further driven to spread the peripheral wedging portions 16 around the upper end of the anvil 55 with the result that the peripheral walls of the shaft 10 adjacent the groove 16 will be spread or enlarged into the groove 16 thus securely locking the shaft 10 within the hosel 14 of the neck 13. By the time the wedging block 20 has been driven to the position with parts occupied as shown in Fig. 5, which will become so firmly seated and embedded on the interior of the shaft 10 within the peripheral grooved hosel opening that the shaft 10 may not be removed from the shank of the club without fracturing the material of the shaft, thus securing a joint that will resist all shocks or strains incident to playing with the club and making a locking joint that is completely hidden from the

exterior of the club shank and dispensing with the unsightly appearance of the exposed ends of rivets or pins that heretofore have marred the appearance of the plated or polished surfaces in the necks of club 70 heads.

Furthermore, it has been found that transverse pins and locking keys introduced through registering openings in the steel shaft and the club head neck are liable to become dislodged and to cut the material of the tubular steel shaft in a manner to promote crystallization of a shaft at this point in the hosel 1.

In Figs. 6 and 7 we show a modified form 80 of locking device for securing the shaft 10 within the hosel of the neck 13 of the club, the latter being provided with the interior peripheral groove 16 as shown in Figs. 2 to 5 inclusive and if the shaft 10 is introduced into the hosel as before described and as shown in Fig. 6, a hardened steel ball 25 is introduced into the open enlarged end of the tapered tubular shaft and forced downwardly by means of a driving rod until the hardened ball 25 reaches the portion adjacent the peripheral groove 16 as shown in Fig. 7. The hardened steel ball 25 will be of a predetermined size adapted to pass through the opening in the shaft 10 with a drive fit in the upper end of the shaft 15 and by driving the ball further until it registers within the plane passing through the widest portion of the groove 16, it will spread the material of the tubular shaft 10 into the groove 16 as indicated at 26 in Fig. 7. This will result in an enlargement of the shaft at this point that will effectively prevent the removal of the shaft by an outward pull since the portion expanded within the groove 16 will be larger than the diameter of the hosel opening at the upper end of the groove 16 so that the shaft will be permanently locked in the hosel in the shank portion of the club head and may not be removed without a failure of the material of the shaft when the locking ball is of the proper size before being driven into that portion of the shaft adjacent the peripheral locking opening 16.

In order that the invention might be understood, the preferred embodiments have been described but it is not desired to be limited to the details except as set forth in the claims since it will be apparent that persons skilled in the art may resort to certain modifications without departing from the purpose and spirit of our invention.

We claim:

1. In a golf club, a head portion provided with an elongated neck or shank having a central bore, there being an undercut peripheral groove on the interior of said bore or hosel opening, a tubular metallic handle shaft seated within the hosel opening, and means on the interior of the said tubular handle 125 130

shaft for expanding the walls of said shaft into said peripheral undercut groove therein for locking said tubular shaft into permanent engagement with the said head of the club.

5 2. In a golf club, a head portion provided with an elongated neck or shank having a central bore, there being an undercut peripheral groove on the interior of said bore or hosel opening, a tubular metallic handle shaft seated within the hosel opening and means on the interior of said tubular handle shaft for expanding the walls of said shaft into the said peripheral groove in the said bore or hosel opening for locking said tubular shaft into permanent engagement with the said head portion of the club, comprising a metallic anvil block substantially filling the interior of the tubular shaft from the lower end thereof and when seated upon the bottom of the hosel opening, having the upper end of said anvil block substantially registering with the under cut peripheral groove on the interior of said bore or hosel opening, there being 25 angular wedging surfaces provided on the upper extremity of the said anvil block, and a cylindrical wedging block provided with a bore in the lower end thereof adapted to cooperate with the upper reduced end of the anvil block when the wedging block is forced downwardly thereupon, whereby to expand the adjacent walls of the tubular shaft into locking engagement with the said undercut peripheral groove on the interior of the bore 35 or hosel opening.

3. In a golf club, a head portion provided with an elongated neck or shank having a central tapered bore, there being an undercut peripheral groove on the interior of said bore or hosel opening, a tapered tubular metallic shaft seated within the hosel opening and means on the interior of said tubular handle shaft for expanding the walls of said shaft into said peripheral undercut groove 40 therein for locking said tubular shaft into permanent engagement with the said head of the club, comprising a spherical metallic ball.

4. In a golf club, a head portion provided with an elongated neck or shank having a tapered central bore, there being an undercut peripheral groove on the interior of said bore or hosel opening, a tubular metallic handle shaft provided with a substantially 45 uniform taper at the lower end thereof for co-operating with the said central tapered bore or hosel opening, and a metallic wedging device adapted, when forced into the interior of the lower end of the tubular shaft within the hosel opening, to expand the walls of said tapered shaft into locking engagement with the undercut peripheral groove in the tapered bore or hosel of said golf club head.

5. In a golf club, a head portion provided with an elongated neck or shank having a

central bore there being an undercut peripheral groove on the interior of said bore or hosel opening, a tubular metallic handle shaft seated within the hosel opening, and means on the interior of said tubular handle shaft for expanding the walls of said shaft into the peripheral undercut groove therein for locking said tubular shaft in permanent engagement with the said head of the club, comprising a co-operating pair of wedging blocks, 70 one of which is adapted to be deformed by contact with the other of said blocks to expand the walls of said tubular member adjacent and into said peripheral undercut groove. 75

In testimony whereof, we have hereunto subscribed our names.

ALFRED E. BUHRKE.
ALLEN F. HEETER.
